(57) **CLAIM**

The ornamental design for a wall mount mirror, as shown and described.

DESCRIPTION

FIG. 1 is a right perspective view of a wall mount mirror showing our new design;

FIG. 2 is a front view thereof;

FIG. 3 is a rear view thereof, wherein the broken lines form no part of the claimed design thereof;

FIG. 4 is a left side view thereof;

FIG. 5 is a right side view thereof;

FIG. 6 is a top plan view thereof;

FIG. 7 is a bottom plan view thereof; and,

FIG. 8 is a right perspective view of the wall mount mirror, showing an alternate tilt position of the mirror with respect to the rear mounting base.
